METHOD AND APPARATUS FOR PRODUC-
ING FIRE EXTINGUISHING FOAMLewis G. Morris Timpson, Plainfield, N. J., as-
signor to Pyrene-Minimax Corporation, a cor-
poration of Delaware

Application August 30, 1934, Serial No. 742,041

13 Claims. (Cl. 261—76)

This invention relates to foam-forming methods and apparatus, and particularly to methods and apparatus for generating a stream of foam consisting of relatively stable bubbles, for blanketing fires capable of such treatment, and extinguishing them principally by excluding oxygen from the seat of the blaze. Heretofore it has been common for this purpose to utilize foam-forming chemicals, which react to form a gas 5 that is then incorporated in a stream of water with some suitable stabilizing agent to make foam. According to the present invention, however, a very satisfactory foam may be produced by the use of only water, air and a stabilizing agent, although another suitable gas may be substituted in whole or in part for air if desired.

Prior attempts have been made to produce what may be termed air-foam, by the incorporation of air in water containing saponin or a similar stabilizing agent, but these have not proved altogether successful for fire extinguishing purposes due to the difficulty of supplying an adequate quantity of air to a stream of water. It has been found that in attempting to draw air into a flowing stream of water by the movement of the stream, as it passes through a jet for example, not more than about half enough air is drawn into a stream of sufficient size for fire extinguishing purposes to produce satisfactory foam. Thus a stream of water discharged through a jet orifice of a given diameter will present an outer surface having an area per lineal inch that is a function of the diameter of the stream. The quantity of air that can be entrained in such a stream is necessarily limited by this surface area. To visualize this we may consider a flowing stream as having a large number of indentations in its surface and each of these indentations may be considered to form a pocket to receive air, much as the buckets of an endless conveyor receive their charge of material in passing a loading point. Now the stream having the surface area mentioned will have a certain volume or cubical capacity per inch of length that is dependent upon the square of the diameter. The ratio between this volume and the surface area specified determines the ratio of air to water that will exist in the pipe beyond the point at which air is sucked into the stream.

As stated, this ratio for a jet of suitable diameter for fire extinguishing purposes, say $\frac{1}{2}$ inch, is such as to produce a very poor grade of foam due to the presence of only about half the required amount of air or gas. If the size of the jet is increased the ratio of air to water is even

worse. If the jet is decreased in diameter the ratio of air to water will be improved, but the resulting stream of foam will be too small to be effective for fire extinguishing purposes and the frictional losses in attempting to flow a small stream through a pipe or hose will be excessive.

The present invention has for its primary object the production of a stable, durable fire extinguishing foam of large volume in relation to the water used, by the intermingling of appropriate proportions of air or similar gas, water and a stabilizing agent. Toward this end the invention contemplates so increasing the surface area of a flowing stream of water as to insure entrainment of a sufficient amount of air to produce a most satisfactory foam in appropriate quantity to be effective for fire extinguishing purposes. This may be very effectively accomplished by dividing a stream of water of suitable volume into a plurality of smaller streams, passing each of these separately through a jet arranged to admit air and then merging the streams of water and air into a single stream for ultimate distribution. Saponin or other foam stabilizing agent may be introduced in any convenient way, either in advance of the jets or at one or more of the jets.

Other features, objects and advantages will appear from a description of the invention, together with the accompanying drawing, in which:

Fig. 1 is a vertical section of an apparatus operable in accordance with the present invention; and

Fig. 2 is a transverse section on line 2—2 of Fig. 1.

Before entering upon a description of the particular apparatus preferred for the conduct of my process the principles upon which it is constructed may be more readily appreciated from the following considerations: It may be assumed that a sufficient volume of water for the production of fire extinguishing foam will be supplied by a solid stream of 14 mm. diameter. The flow area of such a stream is approximately 153.9 sq. mm., and the unit surface area will be π times the diameter or approximately 44 sq. mm. per linear mm. If we divide such a stream into six equal cylindrical streams, the flow area of each will be 25.65 sq. mm., which means that the diameter of each must be 5.71 mm. In other words, at a given velocity of flow, six streams of water 5.71 mm. in diameter will deliver the same volume of water per unit time as one stream of 14 mm. diameter.

The unit surface area of each small stream is equal to π times the diameter or approximate-

ly 17.94 sq. mm. per linear mm. The combined unit surface area of all six streams will then be 107.64 sq. mm., or nearly two and one-half times that of the solid 14 mm. stream. Since one of the six streams is not exposed to the air, the unit surface area available for entraining air is 89.7 sq. mm., slightly more than twice the unit surface area of the solid 14 mm. stream. It is thus apparent that by the use of the present invention it is possible to entrain a much greater volume of air in a given volume of water, and thus produce a greater quantity of foam and one having better body.

It should be noted that the above dimensions are not in any way critical, and a larger or smaller number of streams, or streams of varying dimensions, may be used. Likewise it is not necessary to use cylindrical streams, which are specified herein merely for purposes of illustration.

The apparatus illustrated in the drawing is suitable for carrying out the present invention. Referring to Fig. 1, water from any suitable source, and under suitable pressure, is brought into a jet chamber 10 through a supply conduit indicated at 11. The chamber 10 is defined by a bell member 12 and a jet disc 13, threaded into the mouth of the member 12. A plurality of air ejector nozzles 14 are suitably secured in apertures extending through the jet disc 13. In the present instance five nozzles 14 are arranged in a symmetrical manner around the center of the disc as illustrated in Fig. 2. Other arrangements may be employed if desired. In addition to the nozzles 14, a nozzle 15, for use in introducing a stabilizing agent into the stream, and which for convenience will be called a soap ejector nozzle, is similarly secured centrally of the jet disc 13. A packing gland 150 is preferably provided around each of the nozzles 14 and 15 and any suitable means may be employed for preventing leakage between the bell 12 and disc 13.

Opposite each of the nozzles 14, but spaced a short distance therefrom, is a receiver 16, which together with its associated nozzle 14 comprises an ejector for the entrainment of air. As shown, the receivers 16 are preferably provided with passages having a constricted portion between flaring portions at the two ends. The receivers 16 are secured in suitable apertures of a receiver disc 17, which is supported in the mouth of a bell member 18. The receiver disc 17 and bell member 18 define a receiver chamber 19. Spacer rods 20 connect the jet disc 13 and receiver disc 17, and maintain the nozzles 14 and receivers 16 in proper relationship. If desired the space between the ends of the bells 12 and 18 may be partially enclosed in any suitable way so long as provision is made for the ready access of air or other gas around the receivers 16.

A receiver 21, arranged centrally of the receiver disc 17 in direct line with the nozzle 15, differs from the receivers 16 in that it is provided with an enlarged bell end 22, which is adapted to seat within an annular flange 23 formed upon the face of the jet disc 13, thus sealing to the air the ejector formed by the nozzle 15 and receiver 21. A conduit 23 is tapped into the bell end 22 of receiver 21, and is connected to a suitable supply of saponin or other foam-stabilizing agent.

In the operation of the apparatus described, water under suitable pressure is introduced through the conduit 11 into the jet chamber 10, from which it issues in six separate jets through the nozzles 14 and 15. As the jets from nozzles

14 pass into their respective receivers 16 they entrain in their exposed surfaces a quantity of air, or such other gas as surrounds the apparatus. The jet from the nozzle 15 entrains and takes up a quantity of saponin or other foam-stabilizing agent which is supplied through conduit 23, and all of the jets are again merged in the receiver chamber 19. As the stream thus formed flows out through a discharge conduit 24, the gas and stabilizing agent are distributed throughout the stream, forming a stable foam. It is apparent that the volume of foam thus formed is greater than would be possible by the use of a single solid jet of water and the absence of excess water lends better body and durability to the foam produced.

While the form of apparatus described in detail is considered the preferred construction it will be appreciated that various changes may be made. For example, the foam stabilizing jet 20 might be arranged in advance of and in series with the group of air jets instead of in parallel therewith or the stabilizer might be added by means of a force pump on either the high or low side of one or more of the air jets. Furthermore the separate receivers for the jets might be replaced by a single large receiver.

The terms and expressions employed herein are used for purposes of description and not of limitation. It is recognized that many modifications of the construction disclosed may be made within the scope of the present invention as defined by the claims which follow.

What is claimed is:—

1. In apparatus for producing fire extinguishing foam, a plurality of ejectors, means for passing a stream of water through each of said ejectors, means for introducing a foam-stabilizing agent into one of said streams, means for introducing a gas into the remaining of said streams by aspiration, and means for merging said streams in a single discharge conduit. 35

2. In apparatus for producing fire extinguishing foam, a jet chamber, means for supplying water to said jet chamber, a plurality of nozzles 45 piercing a wall of said jet chamber, a receiver chamber, a plurality of receivers piercing a wall of said receiver chamber and extending toward said nozzles, each of said receivers registering with one of said nozzles, means for introducing foam stabilizing material into said receiver chamber and a discharge conduit leading from said receiver chamber. 50

3. In apparatus for producing fire extinguishing foam, a jet chamber, means for supplying 55 water to said jet chamber, a plurality of nozzles piercing a wall of said jet chamber, a receiver chamber, a plurality of receivers piercing a wall of said receiver chamber and extending toward said nozzles, each of said receivers registering with one of said nozzles, means for supplying a foam stabilizing agent to one of said receivers, means for supplying a gas to a plurality of said receivers, and a discharge conduit leading from said receiver chamber. 60

4. In apparatus for producing fire extinguishing foam, a jet chamber, means for supplying water to said jet chamber, a plurality of nozzles piercing a wall of said jet chamber, a receiver chamber, a plurality of receivers piercing a wall of said receiver chamber and extending toward said nozzles, each of said receivers registering with one of said nozzles, means for supplying a foam stabilizing agent to one of said receivers, the remaining receivers being in open communication with the discharge conduit. 70

- cation with the atmosphere, and a discharge conduit leading from said receiver chamber.
5. In apparatus for producing fire extinguishing foam, means for supplying a stream of water, means for dividing said supply stream into a plurality of secondary streams, means for introducing a foam-stabilizing agent into one of said secondary streams, means for introducing a gas into others of said secondary streams by aspiration, and means for merging said secondary streams to form a single discharge stream.
6. In apparatus for producing fire extinguishing foam, means for supplying a stream of water, means for dividing said supply stream into a plurality of secondary streams, means for supplying a gas under substantially atmospheric pressure to the outer surfaces of a number of said secondary streams, means for merging said secondary streams to form a single discharge stream, and means for aspirating a foam stabilizing agent into one of said streams.
7. In apparatus for producing fire extinguishing foam a plurality of receivers, means for passing a stream of water through each of said receivers, a plurality of said ejectors being arranged to entrain a gas in the outer surfaces of said streams by aspiration, means for merging the streams from all of said receivers into a single stream, and means for supplying a foam stabilizing agent into the water in one of said streams.
8. A method of forming fire extinguishing foam which comprises splitting a flowing stream of water into a plurality of separately confined smaller streams, introducing a gas into a number of said streams by aspiration, merging said smaller streams into a single stream, and adding a foam stabilizing agent to said merged stream.
9. A method of forming fire extinguishing foam which comprises splitting a flowing stream of water into a plurality of separately confined

smaller streams, introducing a gas into a number of said streams by the action of the flow thereof, merging said smaller streams into a single stream, and adding a foam stabilizing agent to one of said streams.

10. A method of forming fire extinguishing foam which comprises splitting a flowing stream of water into a plurality of smaller streams, entraining a gas in the outer surfaces of a number of said streams by aspiration, merging said smaller streams into a single stream, and adding a foam stabilizing agent to one of said smaller streams.

11. The method of forming fire extinguishing foam comprising dividing a stream of water into a plurality of smaller streams, aspirating air independently into a number of said smaller streams, introducing foam stabilizing ingredients into another of said streams, and finally merging all of said smaller streams into a single large stream.

12. In apparatus for producing fire extinguishing foam, a plurality of receivers exposed to the atmosphere, a plurality of nozzles, means for passing a stream of water through each of said nozzles into said receivers, means for merging the resulting streams in a single discharge conduit, and means for introducing a foam stabilizing agent into said merged stream.

13. In apparatus for producing fire extinguishing foam, a plurality of receivers exposed to the atmosphere, a receiver sealed off from the atmosphere, means for passing a stream of water through a separate nozzle into each of said receivers, means for introducing a foam-stabilizing agent into said sealed receiver, and means for merging the resulting streams in a single discharge conduit.
